FIG. 5

FIG. 6

FIG. 7

FIG. 1 is a front elevation of a lenticular shade for a night light embodying my new design;

FIG. 2 is a view similar to FIG. 1 with the shade in a slight perspective to show the lenticular change in the design;

FIG. 3 is a side elevation of one side of the shade;

FIG. 4 is a side elevation of the other side of the shade;

FIG. 5 is a rear view of the shade;

FIG. 6 is a top plan view of the shade; and

FIG. 7 is a bottom plan view of the shade.

The night light is shown in broken lines in FIGS. 1 and 3 for illustrative purposes only and forms no part of the claimed design.

I claim:

The ornamental design for a lenticular shade for a night light, as shown and described.
